ELECTRON DISCHARGE DEVICE

Edgar K. Wimpy, Fairmont Farms, W. Va., and
 Leo C. Werner, Bloomfield, N. J., assignors to
 Westinghouse Electric Corporation, East Pitts-
 burgh, Pa., a corporation of Pennsylvania

Application November 20, 1944, Serial No. 564,242

8 Claims. (Cl. 250—27.5)

1

This invention relates to electron discharge devices, and particularly to such devices having an adjustable electrode therein.

It is a known fact that even though every possible effort is exercised in manufacture of electron discharge devices to duplicate structure and conditions in a series of such devices, there is always some discrepancy between the characteristics of the finished products. As a result, many tubes are rejected after completion which would be usable if it were possible to effect appropriate adjustment without having to disturb the vacuum seal of the device. Such a desideratum assumes greater importance in the larger sizes and more expensive types of devices such as high power amplifiers. For such use, a high mu or amplification factor is essential, and that in turn is sensitive to variation in the grid circuit. Positional alteration of the grid has direct influence upon the grid circuit. Human skill has not attained that degree of perfection which enables grids to be manufactured and mounted invariably accurately and thus different tubes will present different impedances or other tube characteristics.

The principal object of the invention is to enable a sealed electron discharge device to have an electrode therein adjustable to improve tube characteristics of the finished device.

More specifically, an object of the invention is to provide an adjustable grid of improved character.

Another object of the invention is to provide a grid adjustable as to diameter.

Yet another object of the invention is to maintain the grid when adjusted parallel to its previous position.

Again, an object of the invention is to provide improved operating means for effecting the grid adjustment.

Still further objects of the invention will appear to those skilled in the art to which it pertains as the description proceeds, both by direct recitation thereof and by inference from the context.

Referring to the accompanying drawing, the figure thereof is a vertical sectional view of a triode amplifier illustrative of an electron discharge device and showing our invention incorporated therein and likewise shown in vertical section.

In the specific embodiment of the invention illustrated in said drawing, the reference numeral 10 designates a glass or other envelope which is sealed and evacuated. From the bottom of this

2

envelope protrude a plurality of glass nipples 11 in the lower ends of which are sealed the edges of thimbles or prongs 12 which constitute the exterior electrical connections for internal parts. Posts 13 of appropriate length extend from the thimbles 12 upwardly inward of the envelope, certain of the posts carrying transverse brackets 14, which in turn support upright rods 15, at the upper ends of which are transverse parallel bus plates or rings 16 to which the ends of filament or cathode legs 17 are secured. The several filament legs are shown in a sequential series as a cathode assembly in the form of a bird cage symmetrically disposed about a common axis which is the central axis of the device. Other of posts 13 support an anode 18 coaxial to and at a distance from the cathode assembly.

Located in the region between the cathode assembly and the anode and coaxial therewith is a cylindrical grid assembly comprising a sequential series of longitudinal wires 19 all parallel to each other and to the axis. According to the present invention, these several grid wires are adjustable laterally; that is, in a direction radial to the axis. It is by virtue of this adjustment that the tube characteristics may be changed since different spacing of the grid from the other electrodes effects a change of impedance. It is a feature of the invention that these several grid wires may be moved but retain parallelism to the axis.

Mounting for the grid is accomplished by certain fixed parts and by movable parts. The fixed parts are shown as plates transverse to and centralized on the axis, one such fixed plate 20 being shown above the cathode assembly and another fixed plate 21 being shown below the cathode assembly between the bus rings 16 and brackets 14. This lower fixed plate 21 is carried on upright rods 22 similar to previously described cathode supporting rods 15 and similarly supported from one of the posts 13. The upper plate 20 is shown fixed in suspended position above the cathode on an axially located rod 23 which is sealed in the upper part of the envelope 10.

For each grid wire is provided a pair of pivoted arms 24, one arm at the upper end of the wire and one at the lower end. Said arms 24 of each pair are parallel to each other and swing in a plane extending radially from and including the axis. Pivoting of the upper arm is effected in upper plate 20 whereas pivoting of the lower arm is effected in lower plate 21.

The grid wire is stiff and therefore swinging one arm will swing the other, and thus the grid wire is shifted in a radial plane in constant parallelism to the axis.

In order to swing said arms 24 and shift all of said grid wires simultaneously and equally, each lower arm 24 has a link 25 pivotally attached at an appropriate part of the arm, for instance at the pivoting of the grid wire to the arm, the several links being pivotally connected at their other ends to a movable plate 26. As shown, said movable plate is parallel to and below lower fixed plate 21 and centered on the common axis. Both said plates 21 and 26 have suitable apertures therethrough for clearance purposes for such fixed rods 15 and 22 as pass therethrough.

At the middle of movable plate 26 is secured a supporting and controlling stem 27 which extends axially through the bottom of the envelope, so that raising or lowering said stem correspondingly moves the movable plate and thereby actuates the several links which in turn swing the grid supporting arms and shift the grid wires laterally.

Said stem 27 is rendered longitudinally movable by means of a bellows seal 28, the inner end of which is shown sealed to the stem and the outer end of which is shown sealed to a fixed nut 29 having external screw threads. The nut 29 is peripherally soldered to a sleeve 30 situated around the bellows, said sleeve being sealed to the glass envelope. Overlying the threaded surface of the nut is a rotatable and internally threaded cap 31. Said stem is mounted rotatably through the transverse end wall of said cap and is shouldered at 32 to have bearing against the inside of said wall and has a collar 33 on the outside of said wall necessitating that the cap and stem move longitudinally together. By virtue of the threaded engagement of the cap with the fixed nut 29, rotation of the cap obtains longitudinal adjustment of the stem, which, as explained above, obtains the desired lateral adjustment of the grid wires.

We claim:

1. An electron discharge device comprising an evacuated envelope, a cathode, grid and anode in said envelope, said grid having wires parallel to and substantially equidistant from the cathode axis, adjustable means mounting said wires movably for movement toward and away from the cathode and its axis and mounted to maintain said wires substantially in constant parallelism and to simultaneously move all of said wires equal amounts, and adjustable exterior means connected to said mounting means for operating said mounting means and for thereby changing the relation of said grid wires to the cathode and cathode axis.

2. An electron discharge device having a cathode and an anode, a grid between said cathode and anode, said grid having wires parallel to the cathode axis, adjustable means mounting said wires movably for movement toward and away from the cathode and its axis in constant parallelism to the axis thereof, and adjustable exterior means connected to said mounting means for operating said mounting means and for thereby changing the relation of said grid wires to the cathode and cathode axis.

3. An electron discharge device comprising a cathode and anode and a grid having a plurality of wires parallel to the cathode axis, parallel arms pivotally supporting ends of a grid wire, said arms being pivotally mounted whereby said grid wire supported thereby is movable laterally as

said arms swing, and means connected with, and for swinging, one of said arms.

4. An electron discharge device comprising an axially disposed cathode, anode and grid, said grid being radially expandable and contractable, fixed plates mounting said grid, and means extending from said plates to said grid and movable with respect to both said plates and grid, said means supporting the grid from the plates and providing the expanding and contracting radial adjustment for said grid.

5. An electron discharge device comprising an axially disposed cathode, anode and grid, fixed plates above and below said cathode transverse to and centered on said axis, said grid having a plurality of wires parallel to said axis, and arms extending from and pivoted to said plates and wires, the pair of arms for each said wire being parallel to each other, a movable plate, and links extending from the movable plate to the arms pivoted to one of the fixed plates whereby moving said movable plate swings said arms and shifts the said wires laterally.

6. An electron discharge device comprising an axially disposed cathode, anode and grid, fixed plates above and below said cathode transverse to and centered on said axis, said grid having a plurality of wires parallel to said axis, and arms extending from and pivoted to said plates and wires, the pair of arms for each said wire being parallel to each other, a movable plate, and links extending from the movable plate to the arms pivoted to one of the fixed plates whereby moving said movable plate swings said arms and shifts the said wires laterally, and means connected with, and for moving, said movable plate and thereby shifting all said grid wires simultaneously.

7. An electron discharge device comprising a sealed envelope, a cathode, anode and grid therein coaxial to a common axis, said grid having a plurality of wires parallel to said axis and movable laterally for adjustment thereof toward and from the cathode, fixed plates above and below said cathode transverse to and centered on said axis, arms extending from and pivoted to said plates and wires, a movable plate below the plate below the cathode, a stem secured to said movable plate and extending to the exterior of the envelope, and links extending from the said movable plate to the arms pivoted to the said plate below the cathode, whereby axial displacement of said movable plate may be effected by said stem from the exterior of the envelope and whereby said displacement communicates movement to said arms and grid wires and moves the grid wires laterally.

8. An electron discharge device comprising a sealed envelope, a cathode, anode and grid therein coaxial to a common axis, said grid having a plurality of wires parallel to said axis and movable laterally for adjustment thereof toward and from the cathode, fixed plates above and below said cathode transverse to and centered on said axis, arms extending from and pivoted to said plates and wires, a movable plate below the plate below the cathode, a stem secured to said movable plate and extending to the exterior of the envelope, and links extending from the said movable plate to the arms pivoted to the said plate below the cathode, whereby axial displacement of said movable plate may be effected by said stem from the exterior of the envelope and whereby said displacement communicates movement to said arms and grid wires and moves the grid wires laterally, and rotative screw threaded means at the exterior of said envelope connected with said

stem for applying longitudinal movement to said stem.
